GRINDING MILL

Elmer L. Van Pelt, Denver, Colo., assignor to
American Ball Mill Company, Denver, Colo.

Application March 23, 1931. Serial No. 524,549

3 Claims. (Cl. 83—9)

This invention relates to sectional structures and more particularly to locking means for fastening the sections together.

It is an object of the invention to provide a locking means easily applied and permitting of the removal of any one section of a structure separately and without disturbing the other sections.

Another object is to provide a locking device which is adjustable to compensate for expansion and contraction of the material of which the sections are composed and which will resist deflection and deformation of the parts to which it is applied.

15 The invention is particularly adapted for use in connection with linings of ball mills and further objects reside in providing in cooperation with the locking devices, holding means upon which the sections are assembled and which relieve the sections of much of the stresses to which they are subject in the operation of the mill.

Other objects reside principally in novel details of construction and in novel combinations and arrangements of parts as will be brought out 25 in the course of the following description.

In the accompanying drawings in the several views of which like parts are similarly designated,

30 Figure 1 represents a partially sectional side elevation of a ball mill equipped with a sectional lining constructed in accordance with the present invention.

Figure 2, an enlarged plan view of a portion of the lining,

35 Figure 3, a further enlarged section on the line 3—3, Figure 2,

Figure 4, a section along the line 4—4, Figure 2,

40 Figure 5, a sectional elevation showing the application of the locking device to a flat sectional structure,

Figure 6, a section taken on the line 6—6, Figure 5,

45 Figure 7, a side view of one of the sections, showing a modification of the wedge-shaped key forming a part of the locking device.

Figure 8, a fragmentary section through two adjoining sections showing another modification of the key,

50 Figure 9, a similar sectional view in which the sections of the structure are of modified construction, and

Figure 10, a section along the line 10—10,

Figure 9.

55 Referring first to Figures 1 to 4 of the draw-

ings, the ball mill 5 is composed of a cylindrical shell 6 closed at its ends by heads 7 and mounted for rotation on standards 8. A gear wheel 9 exteriorly of the shell, provides means for its rotation by connection with a conveniently located driving element.

The lining of the shell is composed of sections 10 assembled in rows lengthwise of the shell, upon girders 12. The girders are of channel form and they are welded in an inverted position upon the interior surface of the shell as at 13. The girders extending lengthwise of the mill, are equidistantly spaced and they provide saddles for the sections of the lining which are flanged to straddle the same.

60 The flanges of the sections fit snugly upon the sides of the girders but their inner surfaces diverge to facilitate placement of the sections upon the girders and to permit of a certain degree of self-adjustment. When the sections are in place upon the girders, their sides are substantially parallel and spaced from each other. Each section has upon its upper surface, a longitudinal boss 14 which in conjunction with similar bosses of the other sections in the row provide lifters which in 65 the operation of the mill lift and drop the material in a cascading movement.

70 The sections have in their spaced sides curved grooves 15 of tapering depth, the ends of which open at the top of the sections. Wedge-shaped, 75 curved keys 16 driven into the grooves of opposite sections constitute the locking means which fasten the sections in place upon the girders.

75 The ends of the curved keys may project above the surfaces of the sections and if the keys are made of ductile material, their ends may be clinched upon said surfaces to hold the keys against longitudinal displacement. In any case, the projecting ends are not objectionable in the 80 operation of the ball mill and if the ends are worn away, the keys will still perform their function as before.

85 In fact, the sections may wear to their girders without disturbing the position of the keys since a portion thereof is below the surface of the 90 girders upon which the sections are seated, as best shown in Figures 3 and 4. It will be apparent that when the wedge-shaped curved keys are driven into the correspondingly shaped key ways formed by the opposed grooves of slanting depth, 95 in the sides of the sections, these sections are firmly driven against the edges of the girders upon which they are seated and thereby are locked in place.

100 When a section breaks or becomes worn it is 110

easily removed without disturbing adjoining sections, by driving the keys out of the grooves of the section and the worn or broken section is readily replaced by another to be fastened in place by means of the keys as before.

The girders upon which the sections are assembled receive most of the impact of the grinding bodies and the material in the operation of the mill.

10 The girders provide a shell construction which is simple, strong, durable and easily repaired and the keys, owing to their curved form, resist deflection and, moreover, compensate for expansion and contraction of the sections.

15 It is possible to make the keys of pliable material and straight, in which case they will assume the curvilinear form of the key-ways when driven thereonto, as has been illustrated at 17 in Figure 7.

20 The keys may also be made of single or double dove-tailed section to aid in locking the sections against lateral displacement, as has been shown at 18 in Figure 8. This form of the keys is of special nature where the sections are mounted without the girders shown in Figure 3.

25 The sections may be modified by omitting the curved grooves and substituting therefor curved flanges 19 of tapering width, to be engaged by the correspondingly formed keys, as illustrated in Figures 9 and 10. In this form of the invention, the keys engage upon the surface upon which the keys are supported either directly or through the intermediary of girders or similar devices.

In Figures 5 and 6, the locking means are applied to sections 20 of a flat structure, such as a paving or tiling. In this illustration, the girders have been omitted, and the sections are held in place by other means, such as abutments at the edges of the structure.

80 Having thus described my invention, it will be understood that other modifications and changes in construction may be made without departing from the spirit and scope of the invention, as defined by the hereunto appended claims.

85 I claim:

1. A ball mill comprising a shell, girders upon the inner surface thereof, a lining for the shell composed of sections seated on the girders, and wedging keys between the sections for locking them in place.

90 2. A ball mill comprising a shell, a lining for the shell, composed of sections seated in rows within the shell, opposite sections in the rows having curved grooves of tapering depth, forming complementary parts of wedge-shaped key-ways, an opening at the inner surface of the lining, and curved keys in the key-ways, extending continuously between the openings of the same.

95 3. In a sectional structure, spaced sections having curved grooves of tapering depth, forming complementary parts of a wedge-shaped key-way, and having openings in a surface of the sections, and a curved wedge-shaped key in the key-way, extending continuously between the openings of the same.
